UNITED STATES PATENT OFFICE.

GEORGE EDICK, OF ALBUQUERQUE, NEW MEXICO.

RAIL-JOINT.

1,155,903.

Specification of Letters Patent.

Patented Oct. 5, 1915.

Application filed January 25, 1915. Serial No. 4,371.

To all whom it may concern:

Be it known that I, GEORGE EDICK, a citizen of the United States, residing at Albuquerque, in the county of Bernalillo and 5 State of New Mexico, have invented new and useful Improvements in Rail-Joints, of which the following is a specification.

The present invention relates to improvements in safety rail joints, and the primary 10 object of the invention is to simplify and improve the construction of rail joints upon which I received Letters Patent of the United States No. 1,109,407, granted me September 1, 1914.

15 A further object of the invention is to provide a simple, comparatively cheap and thoroughly effective means for connecting the meeting ends of two rails, wherein the employment of nuts and bolts or analogous 20 devices which are liable to become loosened under the constant strain to which the joint is subjected, will be dispensed with and positive holding means of a simple construction substituted therefor.

25 A still further object of the invention is to construct a rail having the underface of its head formed with reverse tapering channels which are adapted to receive the beveled edges of a rail joint and an angle bar, 30 associated with the chair, spring means being employed for securing the angle bar upon the chair and both the chair and angle bar connected to the rails, and whereby the heads of the rails will be relieved from unnecessary strain and a lateral movement of either of the chair members or angle bar 35 effectively prevented.

It is a still further object of the invention 40 to provide a rail joint wherein the parts may be easily and quickly assembled to secure the meeting ends of the rails without necessitating the employment of artisans especially skilled or trained for such a purpose.

45 Other objects and advantages will present themselves as the nature of the invention is more fully understood, reference being had to the accompanying drawings in which there is illustrated a simple but satisfactory 50 reduction of the improvement to practise as it now appears to me, it being, of course, understood that I am entitled to such changes in size, proportion, etc., as fall within the scope of the annexed claims.

55 In the drawings: Figure 1 is a side eleva-

tion, partly in section, illustrating a rail joint constructed in accordance with the present invention showing the means whereby the spring securing member is actuated and held in inoperative position to permit of the assemblage of the parts of the joint, Fig. 2 is a similar view but illustrating the spring in locking position, Fig. 3 is a top plan view of the same, Fig. 4 is a bottom plan view of the same, Fig. 5 is a transverse 60 sectional view approximately on the line 5—5 of Fig. 2, Fig. 6 is a sectional view on the line 6—6 of Fig. 4, and Fig. 7 is a detail perspective view of a portion of the removable side plate for the chair.

In the illustrative embodiment of the invention 1—1 designates two railway rails which are generally of the ordinary construction, but which have the underfaces of their heads in cut or channeled toward their webs, as at 2. The webs of the rails are provided adjacent their ends with the usual bolt openings 3.

The numeral 4 designates a rail chair which has one of its longitudinal edges provided with a vertically straight flange 5 and its opposite edge formed with an angular flange 6, the said angular flange having its upper edge beveled to be received in the channels upon one side of the rail and the 80 vertical plate of the angular flange 6 is formed with outwardly projecting studs 7 which are adapted to be received in the bolt openings 3 in the webs of the rails. The said vertical plate of the flange 6 is 85 preferably formed with a central elongated recess or depression to receive a spring bond 8 to electrically connect the rail ends. The base 9 of the chair 4 is provided with a longitudinal depression or channel 10, the outer 90 longitudinal wall of which being arranged flush with the inner vertical face of the flange 5 and the said outer wall of the channel is arranged at an angle with respect to the chair; that is, the channel is wider at one end of the chair than at the opposite end thereof. The horizontal face of the channel 10 is provided at an equal distance 95 from its ends with substantially bayonet-shaped slots 11—11, and the vertical inner face of the flange 5 is provided with depressions 12—12 which communicate with the outer enlarged portions of the said bayonet slots. The depressions open to the upper 100 edge of the flange 5, and while their inner 105

110 edge of the flange 5, and while their inner

transverse walls may be substantially vertically straight their outer transverse walls are inclined upwardly and outwardly, as indicated by the numerals 13—13.

5 The numeral 15 designates a removable angle bar or side member. The member 15 includes a base 14 in the nature of a wedge plate and which is arranged beneath the angular base flange engaging member and the 10 said base 14 at the juncture of the vertical inner member of said base 14 with the said overlying flange is formed with a thickened portion or extension 16, the same having its outer face or wall 18 beveled or inclined 15 from one of the ends of the member 15 to the opposite end thereof, and the upper horizontally straight wall of said portion 16 is provided with transverse teeth 17. The base 14 as well as its extension 16 is adapted 20 to be received within the channel 10, the inner edge of the base contacting with the inner and longitudinally straight wall of the channel, while the outer edge or face 18 engages with the outer and beveled wall of said 25 channel 10. It is, of course, to be understood that the member 18 is inserted longitudinally from the widened end of the channel 10 to its proper position upon the chair and also that the base 14 covers the outer inwardly extending openings as well as the 30 longitudinal openings of the bayonet slots which communicate with the channel of the chair, and further that the teeth 17 are arranged flush with the upper face of the base 35 9 outward of the channel 10.

The numeral 19 designates a locking member for the joint, the same being constructed of spring material and comprising an elongated body portion 20, having its ends 40 curved angularly in an upward direction, as indicated by the numerals 21, and the extremities of the said ends are bent laterally at a right angle to the member 19, and the said extremities 22 may be diamond-shaped 45 in cross section or otherwise having their lower or underfaces provided with what I will term teeth. The member 19 is of a length to permit of its angular ends being received within the outer enlarged portions 50 of the bayonet slots 11, while the inclined ends 21 will be received within the elongated portions of the said slot.

The teeth of the angular ends are adapted 55 to be engaged between the teeth 17 of the angle bar 15 and so retain the said angle bar against longitudinal movement in either direction. The angular ends 21 are also received within the depression 12—12 in the vertical flange 5 and the wedge plate 14 confines the same within the depressed portions or pockets provided with the mentioned angular walls 13—13.

It will, of course, be apparent that the angle bar cannot be easily forced against the 60 sides of the rails when the ends of the spring

member 19 exert a full tension in a downward direction toward the face of the chair and to provide for this I employ a suitable instrument, indicated generally by the numeral 23. This instrument comprises a body 70 portion having one of its ends formed with a hook 24. The body is hollow or slotted and at the opposite end thereof is arranged the body of a slid able hook 25. This hook 25 has its free end loosely connected with a 75 lever 26, the said lever being pivoted, as at 27, between the sides of the slotted or hollow body. The lever is provided with a pivot hook-shaped catch member 28 which is adapted to engage with a stud 29 arranged 80 between the plates comprising the hollow body disposed above the movable hook at one end of said body. When the hooks are brought into engagement with the toothed angular portions 22 of the securing member 85 19 the lever is swung upon its pivot to draw the body of the slid able hook within the body of the instrument. Thereafter, the hook catch 28 is swung to engage with the stud 29, thus springing the ends of the securing member toward each other, and as a consequence causing the body 20 thereof to curve so that the engaging or toothed ends 90 of the same may be moved above the upper edge of the flange 5 to permit of the free 95 sliding of the angle bar 15 between the flange 5 and into engagement with the sides of the rail. The upper edge of the vertical plate of the angle bar is beveled, as at 30, so that the same will be received within the channels 2 of the rails 1 in the underfaces of the heads of the rails with which the said angle bar engages.

From the above description, taken in connection with the accompanying drawings, 100 the simplicity of the device, as well as the advantages thereof will, it is thought, be perfectly apparent to those skilled in the art to which such invention appertains without further detailed description.

Having thus described the invention, what I claim is:

1. A rail joint including a chair having one of its longitudinal edges provided with a vertical flange, the second edge provided 115 with an angular rail-engaging flange, rails upon the chair, a spring including a longitudinal body portion having angular ends which are arranged in depressions upon the inner face of the vertical flange, said angular ends of the spring being inturned and provided with teeth, and the said vertical flange having its inner face inclined with respect to the longitudinal plane of the chair, rails upon the chair, a removable angle bar having a longitudinally extending tongue, the outer edge of which being beveled to engage with the inclined inner face 120 of the vertical flange of the chair, the upper wall of the tongue being provided with 125 130

transverse teeth and the said teeth adapted to be engaged by the toothed ends of the spring, and means for securing the rails to the angular plate of the chair.

- 5 2. In a rail joint, a chair upon which the rails rest, said chair having one of its longitudinal edges formed with an angular flange which is received within the fishing spaces of the rails, lugs upon the flange engaging in the bolt openings of the rails, the second longitudinal edge of the chair being formed with a vertical flange which is inclined from one end of the chair to the other end thereof, the chair having a longitudinal 10 channel extending from the said vertical flange, the lower wall of the channel being provided with spaced substantially bayonet-shaped slots, a flat spring member having angular ends adapted to be arranged within 15 the bayonet slots and to be received within the depressions provided upon the inner face of the vertical flange, a wedge-plate filling the channel and closing the outer and longitudinal portions of the bayonet slots, a 20 removable angle bar formed with the wedge plate and having its lower horizontal portion provided with transverse teeth and its outer portions dove-tailed and integral with a longitudinal tongue to engage with the 25 vertical flange and the longitudinal edges of the rail, and means for compressing the 30 ends of the spring member to permit of the

insertion of the rails and angle bar upon the chair, the end of said spring member being provided with lateral extensions provided with teeth which are adapted to engage between the teeth of the angle bar when the spring is permitted to expand.

3. The combination with rails having the underfaces of their heads channeled, of a 40 joint chair for the rail ends including a base having a lateral flange received within the fishing spaces of the rails and which has its upper edge angular and engaged within the channels in the heads of the rail, said chair 45 having its opposite longitudinal edge provided with a vertical flange, the inner wall of which being inclined from one end of the chair to the other end thereof, an angle bar having a beveled lower edge adapted to engage with the inclined inner face of the vertical flange, a spring member having angular arms arranged in depressions in the vertical flange of the chair, said ends of the springs being provided with lateral extensions having their lower portions formed with teeth which are adapted to engage between the teeth of the angle bar.

In testimony whereof I affix my signature in presence of two witnesses.

GEORGE EDICK.
